MEANS OF AND APPARATUS FOR TRANSMITTING MESSAGES THROUGH SUBMARINE
AND LIKE CABLES.

Application filed December 30, 1926, Serial No. 158,045, and in Great Britain January 15, 1926.

This invention relates to the construction of cables and the arrangement of apparatus for transmitting and receiving telegraphic and telephonic messages and has for its object improvements whereby retardation due to electro-static capacity is minimized or avoided.

It has heretofore been proposed to transmit telegraphic messages through a cable consisting of an insulated signalling conductor surrounded by an outer insulated conductor, both of which were electrically charged at the receiving end by an earthed source. The transmitting end of the inner signalling conductor was connected through a signalling key to the terminal of the same sign of an earthed source of electricity of higher potential and the receiving instrument was connected between the receiving end of the said inner conductor and the charging source. With this arrangement the two conductors were normally charged to the same potential at the receiving end but owing to resistance and leakage there was a gradual fall of potential towards the transmitting end of the outer conductor with the result that the inner conductor was not so completely screened from the earth at that end and electrostatic capacity was established between the inner conductor and the earth where this potential drop occurred. When the inner conductor was connected to the signalling source by the operation of the signalling key it was charged to a higher potential than the outer conductor and was afterwards discharged through the receiver at the distant end when the circuit of the transmitting source was broken by the signalling key.

According to the present invention the transmitter is adapted to normally apply a predetermined higher potential to the signalling conductor so as to produce a constant current at the receiving end when no messages are being sent and to increase or decrease the potential of the said current according to whether the signals transmitted are dots or dashes.

According to one mode of carrying the present invention into practice three batteries are employed at the transmitting end, one of which is adapted to apply the normal potential to the signalling conductor and two smaller ones each of which is of a strength equal to the increase and decrease of potential employed for signalling. These two batteries are opposed to each other and are normally connected in series with the main transmitting battery so that the normal potential remains unchanged, when not transmitting.

In order to increase the potential so as to transmit a dot the opposed battery is short circuited or cut out by a suitable transmitting key and in order to decrease the potential so as to transmit a dash the other small battery is similarly short circuited or cut out by another suitable transmitting key. I may however adopt any other known means of varying the potential applied to the line.

In order to transmit and receive telephonic messages a telephonic microphone and receiver are substituted for the telegraphic transmitter and receiver, the normal potential conditions may remain the same in both cases.

I will now proceed to more particularly describe my invention with the aid of the accompanying drawings, in which

Fig. 1 is a diagrammatic drawing showing the improved cable with transmitting and receiving apparatus constructed and arranged according to one mode of carrying out the present invention,

Fig. 2 is a cross-section through the cable, which consists of an inner conductor *a*, and an outer conductor *b* separated from each other by insulation *c* and surrounded by an outer layer of insulation *d* and the usual mechanical protection (not shown).

Fig. 3 is a diagram showing an alternative method of applying a varying potential to the line in transmitting signals,

Fig. 4 shows one method of connecting a thermionic valve amplifier across a resistance which is in series with the signalling conductor at the receiving end,

Fig. 5 is a similar view to Fig. 4, in which a transformer is employed instead of a resistance at the receiving end of the signalling conductor, and

5 Fig. 6 shows an arrangement in which a telephonic transmitter and receiver are employed.

According to the arrangement shown in Fig. 1, *a* is the insulated inner signalling conductor and *b* is the insulated outer conductor which is concentrically disposed around it. The inner conductor *a* and the outer conductor *b* are connected to the positive pole of the earthed battery *f* at the receiving end *R* through potentiometer *g* which is connected across a section of the battery *f* to enable the potential applied to be adjusted.

With this arrangement both conductors 20 *a* and *b* will be constantly charged but the electrostatic capacity to earth of the outer conductor *b* will greatly exceed the capacity to earth of the inner conductor *a* owing to the screening effected by the said outer conductor. This screening however is not so effectual at the transmitting end owing to the fall of potential along the outer conductor *b* due to resistance and current leakage so that the capacity to earth of the inner conductor *a* will be correspondingly greater at the transmitting end. To enable the potential of the outer conductor *b* at both ends to be ascertained an electro-static voltmeter *h* is connected to it at the receiving end and 35 a similar voltmeter *i* is connected to it at the transmitting end.

In order to obtain a suitable fall of potential at the sending end of the outer conductor *b* it may if necessary be earthed 40 through a suitable resistance.

At the sending station *T* the inner conductor *a* is also connected to the positive pole of an earthed battery *j* through potentiometer *o* and also through potentiometers *m* and *n* which control the signalling potentials.

Potentiometer *o* is adjusted to normally apply a predetermined higher potential to the signalling conductor *a* so as to produce 50 a constant current through the signalling conductor *a* and the receiver *u* at the receiving end. The electro-static voltmeter *p* is for the purpose of measuring this normal signal potential.

55 For the purpose of transmitting signals two opposed batteries *k* and *l* of approximately equal value are employed. These are provided with potentiometers *m* and *n* and are connected in series with the battery *j*. Owing to the batteries *k* and *l* being opposed they mutually cancel each other. Potentiometers *m* and *n* are both adjusted to the desired value for signalling which will be measured on voltmeters *q* and *r*.

65 To transmit a signal, the section of the

resistance of potentiometer *n* across which the opposed potential is conducted through the signalling conductor *a*, is short-circuited by closing the transmitting key *s*. This will cause a corresponding rise in the current 70 through the receiver *u* which will indicate a dot or a dash as the case may be. In a like manner the closure of the transmitting key *t* will cause a corresponding reduction in 75 the current through the receiver *u* by short-circuiting the section of the resistance of the potentiometer *m* across which the assisting potential is conducted through the signalling conductor *a*. The impedance indicated at *v* at the receiving end is to compensate for the 80 impedance of the receiver *u*.

The application of the higher potential to the signalling conductor *a* will at the transmitting end, cause a corresponding increase 85 in the effective electro-static capacity between the signalling conductor *a* and the earth thus the signal potential will be bound between the inner conductor *a* and the earth, and will discharge itself to earth through the receiver *u* at the receiving end. 90

According to the arrangement shown in Fig. 3 the two signalling batteries *k* and *l* are transposed and the closure of the transmitting keys *s* and *t* connects one or other of the signalling batteries *k* or *l* in series 95 with the battery *j* through their respective potentiometers *m* and *n*, instead of short-circuiting a section of same as is described and shown in Fig. 1.

The closure of the transmitting key *s* 100 will complete the circuit of the battery *l* through the potentiometer *n* and cause an assisting potential to be conducted through it to the signalling conductor *a* which will cause an increase in the normal current flowing through the receiver *u*. In a like manner the closure of the transmitting key *t* will cause an equal current of opposing potential to be conducted through the potentiometer *m* to the signalling conductor *a* 110 which will cause a corresponding reduction in the normal current flowing through the receiver *u*.

I may employ any other known means of applying a varying signal potential to the 115 line without departing from the spirit of the present invention.

According to the arrangement shown in Fig. 4 a thermionic valve is employed to detect and amplify the received signals. A suitable resistance *w* is interposed between the receiving end of the signalling conductor *a* and the positive pole of the charging battery *f*. The grid 3 of a thermionic valve 1 is connected to one end of the resistance *w* whose 120 opposite extremity is connected to the negative terminal of the filament 2 which is heated by the battery 4. The plate 5, of the valve is connected to one terminal of the receiver *u*, whose other terminal is con- 125 130

connected to the positive pole of the high tension battery 6, and the negative pole of the latter is connected to one side of the filament battery 4.

5 The resistance indicated at v , is to compensate for that of w .

Signals passing through the resistance w are detected by the grid of the valve and amplified in the plate circuit in the usual known 10 manner.

According to the arrangement shown in Fig. 5 a suitable transformer is employed in the place of the resistance w shown in Fig. 4. One end of the primary circuit x 15 of the transformer is connected to the receiving end of the signalling conductor a and its other end is connected to the positive pole of the charging battery j . And one end of the secondary circuit y , is connected 20 to the grid 3 while its opposite extremity is connected to the negative terminal of the filament 2 of the valve 1.

In applying the present invention for the transmission and reception of telephonic 25 signals the normal potential conditions remain the same but instead of the telegraphic transmitter and batteries and the telegraphic receiver described in connection with Figs. 1 to 5 a telephonic transmitter z is inserted 30 in series with the signalling conductor a and the signalling battery j as shown in Fig. 6. At the receiving end a telephonic receiver u^1 , may be inserted in the place of the telegraphic receiver.

35 In order to transmit telephonic signals, the potentiometer o , is adjusted to normally apply a predetermined higher potential to the signalling conductor a so as to produce a constant current through the signalling conductor a and the primary circuit x of the transformer as already described.

One terminal of a telephone receiver u^1 is connected to the plate 5 of the valve 1 and the other terminal is connected to the positive pole of the high tension battery 6, the negative pole of which is connected to one 45 side of the filament battery 4.

The transmitter z , may be of any known kind either of the electro-magnetic or resistance varying type.

50 Sound waves acting on the diaphragm of the microphone z will cause the normal potential of the current flowing through the signalling conductor a to vary accordingly.

55 These current variations in passing through the primary circuit x of the transformer will cause to be induced in the secondary circuit y , impulses which will represent the amount of increase or decrease in the said normal current at the transmitting end.

These impulses will be detected by the grid of the thermionic valve and amplified in the plate circuit of the same in the usual 60 known manner.

I may in some cases employ a transformer of any known design at the transmitting end instead of or in addition to the one described and shown.

Although I have shown only one arrangement in which a telephonic transmitter and receiver are substituted for the telegraphic ones, a similar substitution may be made in all the arrangements herein described. I may also employ any number of amplifying 75 valve stages of known design to give the desired signal magnification.

I claim:

1. Means and apparatus for transmitting 80 messages through a submarine or other like cable comprising a cable having an insulated inner conductor and an insulated outer conductor both of which are connected at the receiving end to an earthed electrical charging source, an earthed electrical charging 85 source of higher potential connected to the inner conductor at the transmitting end, means of varying the potential applied to said inner conductor at the transmitting end and means of detecting the variations of 90 current or potential in said inner conductor at the receiving end substantially as described.

2. Means and apparatus for transmitting 95 messages through a submarine or other like cable according to claim 1 in which the charging source at the transmitting end comprises an earthed main battery connected in series with the inner conductor through two opposed smaller batteries of equal 100 strength each of which is provided with a shunt across its terminals controlled by a signal key by means of which either can be short circuited so as to vary the potential of the charging source, substantially as described.

3. Means and apparatus for transmitting 110 messages through a submarine or other like cable according to claim 1 in which the charging source at the transmitting end comprises an earthed main battery connected in series with the inner conductor through two resistances, and two opposed smaller batteries of equal strength each of which is respectively connected in parallel with 115 one of the said resistances through a signal key by means of which the potential applied to the inner conductor can be augmented or reduced substantially as described.

4. Means and apparatus for transmitting 120 messages through a submarine or other like cable according to claim 1 in which the receiver is connected between the inner conductor and the charging source at the receiving end substantially as described.

5. Means and apparatus for transmitting 125 messages through a submarine or other like cable according to claim 1 in which the variations in potential are detected by a thermionic valve applied to a resistance con- 130

nected between the inner conductor and the charging source at the receiving end substantially as described.

6. Means and apparatus for transmitting messages through a submarine or other like cable according to claim 1 in which the variations in potential are detected by a thermionic valve connected to the secondary circuit of a transformer whose primary cir-

cuit is connected between the inner conductor and the charging source at the receiving end substantially as described. 10

In testimony whereof, I have signed my name to this specification at 61 and 62, Chancery Lane, London, W. C. 2, England, 15 this 15th day of December, 1926.

WILLIAM ESTAUGH.
